UNITED STATES PATENT OFFICE.

BENJAMIN T. STAUBER, OF CONCORDIA, KANSAS.

WINDMILL.

SPECIFICATION forming part of Letters Patent No. 484,826, dated October 25, 1892.

Application filed October 10, 1891. Serial No. 408,326. (No model.)

To all whom it may concern:

Be it known that I, BENJAMIN T. STAUBER, a citizen of the United States, and a resident of Concordia, county of Cloud, and State of 5 Kansas, have invented new and useful Improvements in Windmills, of which the following is a specification, reference being had to the annexed drawings, illustrating the invention, in which—

10 Figure 1 is a face view of a windmill in which my invention is embodied; Fig. 2, a section taken vertically through the hub, spring-case, fixed disk, and upper portions of the gearing-supports, the other portions being taken in elevation at Fig. 1; Fig. 3, an inner end view of one of the wings, the eye-guide thereon, and a section of the deflecting-guide in the eye-guide; Fig. 4, a cross-section of Fig. 2 on line H; Fig. 5, an elevation of 15 the slotted hub and a portion of the shaft on which it operates removed from the other mechanism; Fig. 6, a broken plan view of the spring-case, a top view of a portion of the frame-support, and a plan of the lever by 20 which the wings are put edgewise to the wind.

The nature of invention, construction, and operation of my improved windmill will be 25 fully comprehended by the following detail description.

A B represent the vertical frame-supports, and C the lower horizontal frame-support, which are preferably constructed of iron pipe, and their lower connections are made with 30 an elbow and T-pipe, not unlike the manner of ordinary steam-fitting.

W E represent the shaft of the wind-wheel, which is preferably enlarged at W, where it passes through the sliding hub S. The reduced portion E of the shaft has a bearing in 35 a box D, which is tapped by a screw-thread into an elbow on the upper end of the vertical frame portion A.

Secured to a collar on the inner end of the hub S by means of screws t is what I term a "spring-case" P, which is cylindrical in form and is provided with a flanged head O at its outer end, and the head by means of a hole centrally through it has a reciprocating movement on the shaft portion E. Placed on the spring-case P to bear against the flanged head O is a cylindrical collar I, to

which is jointed, on opposite sides thereof, the links M of loop-lever K, which at its angular portion is pivoted to both sides of the vertical frame-support A. The hub S is provided with a diagonal slot m, which extends through to the shaft W, and in the shaft is affixed a guide-pin n, which extends into the slot and engages the margins thereof. The radial 55 arms R are securely fastened to the larger portion of the hub S, and to the arms R by means of loops 3 3 the wings Q Q, &c., are hung to turn, the outer ends of the arms being firmly secured by tenons or other suitable means to a strong annular metal band V, which firmly supports the arms.

On the shaft W and near to its face end is rigidly affixed a metal disk N, in whose periphery is affixed the same number of curved 70 or segment deflecting-guides d d d, &c., as there are wings to the wind-wheel, and each of these guides passes through and engages an eye-guide a, which is secured to the inner face end of each wing Q.

To the extreme face end of the shaft W and outside of the disk N is rigidly secured a wrist-wheel X, which is held in place to operate by means of a bearing C, whose lower portion is rigidly secured to the inside of the 80 frame-support B. A pump-rod f extends through the support B, and fast to the top thereof is an elongated loop Y, within which the crank-pin Z operates to give to the pump-rod a vertical reciprocating motion.

Within the case P and surrounding the shaft portion E is placed a coil-spring F, the rear end of which butts against a disk H, which is rigidly affixed to the portion E of the shaft, and the other end butts against the 90 inner end of hub S. This spring is the means by which the wings Q are kept sufficiently "face to the wind" to turn the wheel. When there is too much wind, the hub S has given to it a spiral movement backward against the 95 spring, and during this movement the eye-guides a are so directed by the guides d as to turn the wings from the position shown at Fig. 1 to the position shown at Fig. 2. When the excess of wind has ceased, the 100 spring forces the hub S back to put the wing again face to the wind. From this it will be seen that in variable winds the hub S will be constantly moving spirally back and

forth on the shaft portion W, and as the pressure of wind increases the wings present less surface to the wind, and vice versa, and as the result a substantially-uniform velocity of the wind-wheel is attained.

To put the wings of the wheel edgewise to the wind when desired, pull down on the lower portion of K and secure it in that position by cord to any convenient place on the tower below.

It is not thought necessary to represent the turn-table and the tail-vane, inasmuch as the frame portion C can be attached to the ordinary turn-table so as to bring the rod f in the center thereof without instructions. It will be seen that the wind-wheel will lie wholly above the turn-table and that the lower half of the wind-wheel lies within the frame portions A B C. This construction I find to be the best for the support of the mechanism described, and by means of what I term a "pipe-frame" the wind-wheel receives a very firm support with a minimum amount of metal.

Having thus described my invention, I claim and desire to secure by Letters Patent of the United States—

An improvement in windmills, consisting of the U-shaped supporting-frame, the wind-wheel mounted thereon and vertically within the frame, a disk rigidly mounted on the wheel-shaft and curved arms mounted on the disk, the wheel-hub having an oscillating reciprocating movement on the wheel-shaft, and the wings provided with eyes engaging the curved arms, in combination with a coil-spring mounted on the shaft and having its resistance against the larger portion of the shaft, and a disk secured to the shaft, a cylindrical case secured to the shaft, and means for moving the wind-wheel from the fixed disk to deflect the wings, as and for the purpose specified.

BENJAMIN T. STAUBER.
